UNITED STATES PATENT OFFICE.

ROLAND MORRILL, OF BENTON HARBOR, MICHIGAN.

PUMP.

SPECIFICATION forming part of Letters Patent No. 691,652, dated January 21, 1902.

Application filed June 24, 1901. Serial No. 65,799. (No model.)

To all whom it may concern:

Be it known that I, ROLAND MORRILL, a citizen of the United States, residing at Benton Harbor, in the county of Berrien and State 5 of Michigan, have invented certain new and useful Improvements in Spray-Pumps, of which the following is a specification.

The present invention relates more particularly to pumps of the class used for spraying 10 liquid insecticides, but which may be used for spraying water, whitewash, calcimine, paint, and other liquids. These liquids contain more or less gritty matter, and it has been a matter of some difficulty to provide 15 for the purpose described a pump that will meet all of the requirements, including cheapness, compactness, efficiency, durability, simplicity, and ready removability of the valve device for the purpose of cleaning or repairing it.

The object of the present invention is to provide a pump that will meet all of these requirements; and to this end the invention consists in the features of novelty that are 25 hereinafter described with reference to the accompanying drawings, which are made a part of this specification, and in which—

Figure 1 is a vertical section of the lower portion of a spray-pump embodying the invention. Fig. 2 is a plan view thereof. Fig. 3 is a sectional elevation thereof, the valve-casing being shown in elevation and the hollow base in vertical section. Figs. 4 and 5 are perspective views of details.

35 A represents a hollow base having internal threaded annular flanges a and a' , into which the lower ends of the air-chamber B and the plunger-chamber C are screwed, respectively. The bottom of the air-chamber is in direct 40 open communication with the interior of the hollow base, while the bottom of the plunger-cylinder is in direct open communication with the interior of a hollow valve-casing D. This valve-casing is so made that it remains intact 45 when removed from the base, (by preference it is cast in one piece,) so that it may be handled to put it in place with greater facility than would be possible if it were made up of a number of separate and wholly disconnected 50 pieces. The hollow base has a cylindrical portion A', which projects downward and is open at bottom, and above this it has a threaded

opening a'' , which is concentric with the axis of the portion A. The valve-casing has a cylindrical portion D', which fits snugly within 55 the portion A', and below the portion D' it has a shoulder d , which is adapted to come against the bottom of the portion A' and form a tight joint therewith, either with or without the use of a gasket. The valve-casing has also 60 an inclined ceiling D'' and above this a contracted portion D'', which joins the ceiling at one side of the center thereof, whence it proceeds upward and is deflected inward, terminating at top in a contracted cylindrical portion d' , which is in axial alignment with the large cylindrical portion D' and is adapted 65 to enter an opening a'' in the base, the portion d' being externally threaded, so that when screwed into the opening a'' it will form 70 a tight joint therewith and will draw the shoulder d firmly against the lower margin of the portion A' of the base. By these means the interior of the valve-casing is placed in direct open communication with the interior 75 of the plunger-cylinder, and the valve-casing is utilized for the purpose of closing the bottom of the hollow base, the valve-casing proper being contained within said base.

Through the bottom of the valve-casing is 80 a threaded opening, into which is screwed the valve-seat E of the induction-valve F. This valve is provided with a stem f , which extends downward and passes through a spider e , by which it is guided, a cross-head f' being provided at the lower end of the stem for the purpose of limiting its upward movement. Projecting upward from the seat proper are uprights e' , which guide the valve proper, insuring its perfect seating.

85 Through the inclined ceiling D'' of the valve-casing is formed a port d'' , which opens into the hollow base and is controlled by a valve G, having a stem g , which is swiveled in a yoke H, which latter straddles the reduced portion D'' of the valve-casing and is 90 swung from gudgeons h , cast upon the sides of said reduced portion D''.

95 By constructing the parts as shown and as above described the passages for the liquid 90 may be made of ample capacity, while at the same time the entire base and accessories are compact, thus requiring a smaller quantity of metal than is required where the parts are

of any other construction known to me. In addition to this the course which the liquid is compelled to take in first entering through the induction-port and passing thence through 5 the valve-casing into the plunger-cylinder, and then passing back into the valve-casing, through the induction-port, and thence through the hollow base to the air-chamber is more direct than in any other pump of 10 this class known to me. These things are of importance in that they reduce the friction upon the liquid and enable the production of high pressure within the air-chamber.

Another important advantage of the construction above described is that the valves are permanently associated with the casing, so that when the casing is removed the valves will not only be removed with it, but will be retained in place, so that when necessary 20 they may be cleaned and replaced with the least possible manipulation.

The valve-casing has a depending flange or apron I, from which short legs i project downward. This depending flange or apron is provided with an annular groove, into which is sprung the margin of a wire-gauze diaphragm J, which serves to prevent large bodies of solid matter from reaching the induction-port. For the purpose of preventing the pressure 30 of the liquid upon the diaphragm from pressing it upward, so that it would interfere with the movement of the valve-stem f, a number of projections e" extend downward from the valve-seat E.

Having thus described my invention, the following is what I claim as new and desire to secure by Letters Patent:

1. In a pump of the class described, the combination of a cylinder, a hollow base open 40 at the bottom and having an opening opposite the lower end of said cylinder, a removable hollow valve-casing closing the bottom of the base and having a hollow, unvalved portion extending upward to the opening 45 aforesaid and in direct communication with the bottom of said cylinder, said valve-casing being provided with an induction-port opening directly into it and an eduction-port opening into the hollow base, valves for controlling said ports, and a second cylinder, one of said cylinders being an air-cylinder and the other a plunger-cylinder, substantially as described.

2. In a pump of the class described, the 55 combination of a cylinder, a hollow base open at the bottom and having an opening opposite the lower end of said cylinder, a removable hollow valve-casing formed in one piece and closing the bottom of the base, the interior of said valve-casing being in direct open communication with said cylinder, said valve-casing having a valved port communicating with the hollow base and a valved induction-port opening directly into it, a removable 60 valve-seat surrounding said induction-port, and a second cylinder, one of said cylinders

being an air-cylinder and the other a plunger-cylinder, substantially as described.

3. The combination of an air-chamber, a plunger-cylinder, a hollow base, open at bottom and having an opening opposite the lower end of the plunger-cylinder, and a hollow valve-casing closing the bottom of the base and having a hollow portion extending upward and communicating with the bottom of the plunger-cylinder through the opening aforesaid, said casing having also induction and eduction ports, the latter opening into the hollow base, and valves for controlling said ports, substantially as set forth. 80

4. The combination of an air-chamber, a plunger-cylinder, a hollow base having an opening opposite the bottom of the plunger-cylinder, and having a cylindrical portion extending downward in axial alinement with said opening, a hollow valve-casing located within the base and closing said cylindrical portion of the base, said casing having a hollow portion extending into the opening aforesaid at the bottom of the plunger-cylinder, 90 and having also induction and eduction ports, the latter opening into the hollow base, and valves for controlling said ports, substantially as described.

5. The combination of an air-chamber, a plunger-cylinder, a hollow base, open at bottom and having an opening opposite the lower end of the plunger-cylinder, a hollow valve-casing located within the hollow base and closing the bottom thereof, said casing having a contracted portion extending upward and communicating with the bottom of the plunger-cylinder, said casing having also induction and eduction ports, the latter opening into the hollow base, and valves for controlling said ports, substantially as described. 100

6. The combination of an air-chamber, a plunger-cylinder, a hollow base, open at bottom and having an opening opposite the lower end of the plunger-cylinder, a hollow valve-casing closing the bottom of the base and having an inclined ceiling, provided with an eduction-port, opening into the hollow base, a contracted portion joining the ceiling at one side of said port and projecting upward, 110 said contracted portion being deflected inward and communicating at its upper end with the interior of the plunger-cylinder through the opening aforesaid, said casing having also an induction-port, and valves for controlling said ports, substantially as described. 115

7. The combination of an air-chamber, a plunger-cylinder, a hollow base, having an opening opposite the lower end of the plunger-cylinder, and having a cylindrical portion projecting downward and in axial alinement with said opening, a valve-casing closing the bottom of the base and having a cylindrical lower portion located within the base, an inclined ceiling having an eduction-port opening into the base, a contracted portion join- 125

130

ing the ceiling at one side of the center, whence it projects upward, said contracted portion being deflected inward and terminating at top in a cylindrical portion, in axial alinement with its cylindrical lower portion, and entering the opening aforesaid at the bottom of the plunger-cylinder, said casing having also an induction-port, and valves for controlling said ports, substantially as described.

8. The combination of an air-chamber, a plunger-cylinder, a hollow base in open communication with the bottom of the air-chamber, said base having a threaded opening opposite the bottom of the plunger-cylinder, and having also a cylindrical portion in axial alinement with the threaded opening aforesaid, and open at bottom, a hollow valve-casing located within the cylindrical portion of

the hollow base and closing it at bottom, said valve-casing having also a portion projecting upward, and having threaded engagement with the threaded opening aforesaid, said valve-casing having also induction and education ports, and valves for controlling said ports, substantially as described.

9. The combination with the induction-valve, of a stem projecting downward, means for guiding said stem, a wire-gauze diaphragm arranged below the travel of said stem, and projections engaging said diaphragm for holding it in place, substantially as described.
